UNITED STATES PATENT OFFICE.

WILLIAM R. D. McQUARRIE, OF BUFFALO, NEW YORK.

PICTURE SPINNING-TOP.

1,393,148.

Specification of Letters Patent. Patented Oct. 11, 1921.

Application filed February 14, 1920. Serial No. 358,636.

To all whom it may concern:

Be it known that I, WILLIAM R. D. McQUARRIE, a citizen of the United States, residing at Buffalo, county of Erie, and 5 State of New York, have invented certain new and useful Improvements in Picture Spinning-Tops, of which the following is a specification.

My invention relates to spinning tops and 10 particularly to that class thereof wherein the top is adapted to be spun on a fixed pivot. More specifically my invention relates to a top of the class mentioned equipped with means for producing optical illusions.

15 The object of my invention is to provide a top of the class mentioned equipped with pictures so arranged that the objects therein shall appear to be in motion.

A further object of my invention is to provide 20 a device as mentioned which shall be of low cost to manufacture. Other objects will appear hereinafter.

With these objects in view my invention consists generally in a top comprising a 25 rotatable member and pictures supported thereon and arranged to come into view successively as the member is rotated, the objects in the pictures being represented in different positions so as to produce the illusion 30 of motion in said objects as the top is rotated.

My invention further consists in a device as mentioned further characterized by an arrangement of the pictures so that each 35 succeeding picture will act as a shutter to cut off the view of the picture receding from the point of vision. My invention further consists in a device as mentioned of such construction that the pictures are removable, to the end that various pictures may 40 be substituted one for the other. My invention further consists in a top comprising a rotary sheet metal disk, picture holders struck up from said disk and a pivot for 45 said rotary disk. My invention further consists in various details of construction and arrangements of parts, all as will be fully described hereinafter and particularly pointed out in the claims.

50 My invention will be more readily understood by reference to the accompanying drawings forming a part of this specification and in which,

55 Figure 1, is a side elevation of a top embodying my invention, the same being

broken away on substantially the line 1—1 of Fig. 2,

Fig. 2, is a plan view of the device,

Fig. 3, is a detailed plan view of the supporting element of the rotary member before being bent into shape,

Fig. 4, is a perspective view of the same after having been bent into shape,

Fig. 5, is a perspective view of the portion by which the top is rotated,

Fig. 6, is a detailed section on the line 6—6 of Fig. 1,

Fig. 7, is a detailed section on the line 7—7 of Fig. 1, and

Fig. 8 is a detail of the pictures.

Referring now to the drawings, the top comprises a fixed portion 11, and a rotary portion 12. The portion 11 may be of any preferred form. As shown in the drawing it comprises a base 13 and a vertical pin 14 terminating in a pointed end 15. The member 12 comprises a disk 16 formed of sheet metal and preferably provided with a weighted periphery 17. 18 indicates the supporting element of the rotary member. This consists of a cruciform structure comprising a plurality of arms 19, terminating in tongues 20. The members 18 may be stamped of a single piece, or may be formed of two strips crossed and secured 85 together in any suitable manner. At the center of the intersection of the arms, the member 18 is provided with an indentation or recess 21 to receive the point 15. The arms 19 are bent downwardly as shown in 90 Figs. 1 and 4 of the drawings, and the tongues 20 are inserted through slots 22 in the disk 16 and then bent to secure the same thereto. The center of the disk 16 is provided with an opening 23 to permit member 95 14 to pass therethrough. Fixed to the top of member 18 is an actuating piece 24. This preferably consists of a knurled cylindrical member having tongues 25 on its lower end which extend through slots 26 in the member 18, and which are bent under to secure the device in position. It is obvious that by placing the rotary member on fixed pivot with the point 15 in the recess 21, the top may be readily spun by turning the element 100 24 between the thumb and forefinger.

Picture holders are provided on the rotary member 12. These are preferably struck up from the disk 16, as shown in the drawings. As shown therein, a substantially rec-

tangular portion 27 is bent upwardly and provided at its side with tongues 28 and 29 which are bent upon opposite sides of the portion 27 to serve as means for holding pictures upon both sides of the same. Similar tongues 30 are struck up from the bottom thereof upon which the picture may rest. It is obvious that the tongues 30 need only project upon one side of the plate 27, as the disk 10 itself serves as a rest for the bottom edge of the picture on the opposite side of the plate. This construction provides an arrangement whereby the pictures may be readily slipped into position upon both sides of each of the 15 plates 27. I preferably construct this so that the plates 27 are arranged substantially radially on the disk 16.

31 indicates the pictures which may be provided in strips 32 as shown, the strips 20 being scored as at 33 between the several pictures to facilitate separating the same.

As shown in the drawings, the picture is such as to represent a boy chasing a cat. The strip comprises a number of pictures of 25 the boy equal to the number of plates 27, and a corresponding number of pictures of the cat. The pictures of the boy are arranged upon the same side of each of the plates and the pictures of the cat upon the 30 opposite side thereof. Each picture presents the object in a different position so that when the device is rotated the illusion will be produced of motion in the objects. It will be noted that I have illustrated the boy with 35 but one leg and the cat with but two legs. This is advantageous on account of the rapid rotation of the top, as it thereby reduces apparent speed of the motion of the objects, and makes the apparent motion more distinct. It will be also noted that as the top 40 rotates the picture extending more directly toward the observer will serve as a shutter by passing from in front of the picture coming into view on one side and then cutting off the view of the picture receding from view on the other side.

I claim:

1. In a spinning top, a rotatable member, a plurality of radially disposed vertical 50 holders thereon, means for supporting pic-

tures on both faces of said holders, the pictures and holders constituting shutters, substantially as described.

2. In a spinning top a rotatable member comprising a sheet metal disk and supporting member therefor, picture holders struck up from said disk of substantially the same size as the pictures to be used and means for holding different pictures upon opposite sides of said holder, substantially as de- 55 60 scribed.

3. A device as set forth in claim 2 in which the picture holding devices are radially disposed, substantially as described.

4. In an optical illusion device, a plurality 65 of pictures and means for bringing said pictures successively into view, said pictures including objects having members represented in successive positions, and the movable members of said objects being reduced be- 70 low the normal number, as and for the purpose specified.

5. A device of the class described, comprising a vertical pivot member and rotatable member comprising a disk having a 75 centered aperture, a support comprising an end member indented to receive the upper end of the pivot and a plurality of depending arms, the lower ends of said arms being secured to said disk, substantially as de- 80 scribed.

6. A device as set forth in claim 5, in which said supporting element comprises a cruciform member, substantially as de- 85 scribed.

7. A device as set forth in claim 5, in combination with means fixed to the upper end of the supporting means to facilitate rotating the device, substantially as described.

8. A device as set forth in claim 5, in combination with picture holders struck up from 90 said disk, substantially as described.

In testimony whereof I have signed my name to this specification in the presence of two subscribing witnesses.

WILLIAM R. D. McQUARRIE.
